[57] **CLAIM**

The ornamental design for combined audio and video cassette transport container, as shown and described.

DESCRIPTION

FIG. 1 is a perspective view of a combined audio and video cassette transport container showing my new design in its closed configuration;

FIG. 2 is a rear elevational view thereof;

FIG. 3 is a top plan view thereof;

FIG. 4 is a front elevational view thereof;

FIG. 5 is a left side elevational view thereof;

FIG. 6 is a right side elevational view thereof;

FIG. 7 is a perspective view of my new design in its open configuration;

FIG. 8 is a top plan view thereof;

FIG. 9 is a left side elevational view thereof;

FIG. 10 is a right side elevational view thereof;

FIG. 11 is a bottom plan view thereof;

FIG. 12 is a front elevational view thereof; and,

FIG. 13 is a rear elevational view thereof.
